UNITED STATES PATENT OFFICE.

ELBERT BALL PORTER, OF PENN YAN, NEW YORK.

PRESSURE-GENERATOR.

1,132,381.

Specification of Letters Patent. Patented Mar. 16, 1915.

Application filed April 12, 1912. Serial No. 690,322.

To all whom it may concern:

Be it known that I, ELBERT B. PORTER, a citizen of the United States, and a resident of Penn Yan, in the county of Yates and State of New York, have invented a new and Improved Pressure-Generator, of which the following is a full, clear, and exact description.

My invention comprises a system by means 10 of which I produce a pressure medium to be used for power purposes; for example, as the motive agent in prime movers of almost any type; and it has for its primary object the generation of the required pressure in a 15 manner that will avoid all waste and losses and make available for the purpose mentioned every particle of energy generated.

In the practice of my invention I preferably employ a device which includes a suitable chamber wherein fuel is received and burnt. I find it desirable to use gaseous fuel, and I cause the fuel to be put under considerable pressure, so that when the fuel is ignited a gaseous medium consisting of 25 products of combustion at a high pressure results. Part of this medium then forces another medium such as liquid into the same, the temperature of which is high enough to vaporize the liquid, and the total volume of 30 the mixture is greatly enhanced in consequence. The resultant pressure medium consisting of gases at a high pressure is then drawn off and applied as needed.

A further object of my invention is to 35 cause the liquid taken up by the gaseous medium to undergo a preliminary heating before vaporization, so as to avoid lowering the temperature of the gaseous medium beyond a certain degree; and I so arrange the 40 parts of my system that the radiation from the pressure generator is caused to have this effect. I thus conserve all the heat units generated by the process of combustion and am able to apply the entire amount of thermal 45 energy stored up in the pressure medium to the doing of useful work.

My invention is especially adapted to produce a pressure medium which is capable of serving the same purpose as steam, and 50 which consists mainly or largely of steam. To obtain such a medium I first generate gases at high temperature, and cause water to be injected into the same, this water being immediately acted upon by the hot gases and 55 vaporized. The resultant pressure medium will be of greatly increased volume and of

sufficiently high temperature and pressure to be suitable for the purpose mentioned; and it is conducted then from the place of generation to the point into which the water 60 is injected, I employ an apparatus that practically eliminates all waste and loss of heat, and enables me to dispense with the costly and inefficient furnaces and boilers that are 65 commonly regarded as necessary in all steam power installations.

Reference is to be had to the accompanying drawings forming a part of this specification and showing the preferred form of improved generator, the same characters of 70 reference being used to indicate the same parts on all views shown.

Figure 1 is a vertical longitudinal sectional view of my improved generator; Fig. 2 is a horizontal section on the line 2—2 of 75 Fig. 1; Fig. 3 is an end view of the generator; and Fig. 4 is a transverse vertical section taken through the outlet of the generator to show the interior construction thereof.

I shall first describe those parts of my generator by means of which the gaseous medium which I produce is formed. The parts in question comprise one or more chambers of the necessary capacity to which a gaseous combustible mixture is supplied and subsequently ignited, and the parts are so arranged as to be automatic in operation, causing the supply and ignition of the fuel to occur at repeated intervals until the apparatus is stopped. Such parts perform the 80 initial steps in the generation of the pressure medium.

In practice I preferably employ a pair of aligned cylinders having open inner ends with out-turned flanges 2. These flanges 95 are bolted to a central cylinder 3 and form therewith a closed central chamber 3'. In each of the cylinders 1 is a piston 4, this piston 4 being hollow, as shown, and being of slightly less diameter than the internal 100 diameters of the cylinders 1, and each having a flange or collar surrounding the body thereof adjacent the compression end, which is grooved to receive packing rings that fit the bore of the cylinder snugly and prevent 105 any leakage past the piston, as will be readily understood. The outer ends of the pistons 4 are closed and they may rest in contact with each other, as shown in Fig. 1, or they may be joined together or cast in one 110 piece if desired, so as to make them move in unison. Adjacent the abutting ends of the

- pistons 4 is a collar or conical flange 5 for each piston, and these flanges or collars are pierced by radial apertures 6 communicating with the hollow interior of the piston 4.
- 5 Each piston 4 has apertures 7 through the walls thereof adjacent the compression end, and just forward of the collar carrying the packing rings. The apertures 6, when they are uncovered, serve to put the hollow interior of the piston into communication with the interior of the casing 3.
- The compression ends of the pistons 4 are closed by heads 4', which have screw-threaded engagement with the insides of the pistons 4, as shown. The outer ends of the cylinders 1 are closed by partitions 8, which have screw-threaded engagement with the inside of the cylinders and have central apertures to receive valves 9. The valves 9 are beveled and the edge of the apertures in the partitions 8 are also beveled to form the seats for the valves; and to each of the valves 9 is connected a stem 10, which passes to the outside of the cylinder 1. Each of the valves 9 is also provided with a dash-pot attachment to cushion the same on its opening movement, this dash-pot consisting of a plunger 11 carried by the rear face of the valve and fitting into a suitable dash-pot 12 carried by a cross bar 13. This cross bar 13 is mounted in a cylinder head 14, detachably secured to the body of the cylinder 1, and through this cylinder head 14 the valve stem 10 projects. This valve stem 10 has a head 10' on its outer end and a collar 10₁ between the outer end and the head 14, to enable the valve stem and the valve thereon to be operated. The interior of the heads 14 for the cylinders 1 constitutes compression chambers when the valves 9 are closed, and the combustible mixture is forced into these compression chambers under pressure, to be ignited and force the pistons 4 to reciprocate. The interior of each of the cylinder heads 14 is supplied with combustible mixture through a port in the head 14, to which leads an inlet conduit 15. This conduit 15 is connected to a suitable mixer or carburetor 16. There is of course a carburetor 16 for each cylinder 1, and each carburetor is connected to a tank 17 in which is stored gasoline or other hydrocarbon to be mixed with air and form the charge. The carburetors 16 will communicate with air pipes 18 containing check valves 18' and shut off valves 19. Each of the pipes 18 leads from one of the carburetors 16 to the flange 2 of its associated cylinder, 1, into the central chamber 3'. When air is forced 60 through the pipes 18 into the carburetors the air carries a suitable quantity of hydrocarbon into the chambers on the inside of the head 14, and when this mixture is ignited the power is furnished which drives the generator. For the purpose of forcing air

under pressure to the carburetors 16 I employ a pair of suitable pumping pistons 21 in the casing 3'. These pistons 21 are concentric with the pistons 4 and surround the same and can slide to some extent thereon, 70 and they are mounted by screwing them upon the threaded ends of sleeves 22 which inclose the bodies of the pistons 4 between the flanges 5 and shoulders 22' formed by the collars on the compression ends of the 75 pistons to receive the packing rings above referred to. The sleeves 22 are of slightly less length than the distance between the flange 5 and the shoulder 22', to permit the sleeve to have relative movement with respect to the pistons, for a purpose which will be described later. When the piston 4 at the right moves to the right to take the position of the parts shown in Fig. 1, its flange 5 will engage the right piston 21 and move 80 this piston and the sleeve 22 with it after the piston 4 has moved a distance equal to the space between the flange 5 and the end of the sleeve 22; and at the same time the shoulder 22' on the piston 4 at the left will engage 85 the inner end of the sleeve 22 of the left-hand cylinder, and move this sleeve 22 outward with the piston after moving a distance equal to the space between the inner end of this sleeve 22 and the shoulder 22' on 90 the left-hand piston.

The numerals 20 represent air inlet pipes which lead through the walls of the central cylinder 3 to the interior thereof to supply air between the pistons 21 and the flanges 2. 100 Each of these pipes 20 has valves 20' therein to enable the amount of air taken in to be controlled. The pipes 20 will also contain the usual inlet check valves.

Each of the cylinder heads 14 carries a 105 suitable igniter 23, the igniters being preferably of the jump-spark type and being supplied with current from high tension coils, the primaries of which are energized by batteries and circuit closers in the usual way. The circuit closers consist of movable contacts 24 and fixed contacts 25, the former being actuated by projections carried by cross bars 26' on rods 26, of which there are two pairs, the members of each pair being 110 connected to one of the pistons 21 and passing through suitable stuffing-boxes in the flanges 2 of the cylinders 1 for this purpose. The cross bars 26' are perforated and receive the outer ends of the valve rods 10, 115 these cross bars being located between the heads 10' and the collars 10₁ on these rods, to actuate the same when the bars 26' are moved. The bars 26' thus serve to control ignition and to control the valves 9 likewise. 120 I may make the parts 10, 10₁ and 26 adjustable, so as to be better able to regulate the operation of the apparatus. This is apparent to every one skilled in this art.

27 are apertures or ports located in each 130

of the cylinders passing through the top walls of the same. They are located between the flanges 2 and the partitions 8; and 28 are similar but larger ports located between 5 the ports 27 and the flanges 2. Each port 27 communicates with a conduit 29 having a check valve 29' therein, and likewise a shut-off valve 30, and the ports 28 are connected by short lengths of pipes or couplings 31 to 10 couplings 32, which have pipe sections 33 leading from one end of the same. The pipe sections 31 have check valves 31' therein to prevent any return of the gases therethrough.

15 The mechanisms thus far described operate to force fuel into the generator and then ignite the same; and the resulting gaseous medium at high temperature and pressure flows out through the ports 27 and 28, 20 and a small part through openings 7 and 6. This will more fully appear from the detailed account of the operation of my generator, which will be given later.

I shall now take up the manner in which 25 liquid is forced into the gaseous medium to be vaporized by the heat of the same, and add to the total volume thereof. This is accomplished in a positive and certain manner by applying part of the pressure gases to 30 feed the liquid into the body of the gases, the following arrangement being employed.

The numerals 34 represent hollow heads which are screwed into the couplings 32 opposite the pipes 33, and each of the heads 34 35 contains a valve 35. The heads 34 and the valves 35 therein act as atomizer pumping attachments to spray water into gases of combustion formed in the cylinders 1, and each of the heads 34 is accordingly provided 40 with a central conduit 36 terminating in a head 37, this head 37 being screwed into the end of the head 34, which unites with the coupling 32, and being formed to provide a seat for the valve 35. The conduit 36 passes 45 out through the closed end of the head 34, and it is also perforated just behind the head 37 to enable the space between the valve and its seat, when the valve is off its seat, to communicate with the space between its conduit 36 and the inner surface of the head 34.

39 is a valve stem passing longitudinally through the conduit 36 and out through the end thereof, and terminating in a head between which and the end of the conduit 36 55 is a compression spring, this spring normally acting to hold the valve to its seat; and 40 is a nipple which screws over the outer end of the conduit 36 to house the outer end of the valve stem 39 and the spring 60 which it carries.

Each head 34 contains a sliding block or piston 41 which has a bore receiving the conduit 36, and has a snug fit with the inner 85 surface of the heads 34. A stop 41' is provided to limit the movement of the piston 41

toward the head 37, and 42 represent springs which normally hold the plungers or pistons 41 against the stops 41'. The conduits 36 have apertures or ports 42 in the section of their length between the end of the heads 34 70 and the pistons 41; and 44 represent pipes which communicate with water tanks 46 and have shut-off valves 45 therein. These pipes 44 supply water to the space adjacent the closed outer ends of the heads 34, and this 75 water passes through the apertures or ports 42 into the conduit 36 and out through the end thereof when the valve 35 opens.

The pressure of part of the gases flowing through the pipe 29 opens valve 35, and at 80 the same time actuates the piston 41 at each end of the generator; and liquid is thus forced into the main body of the gases flowing through the pipe 31, as will more fully hereinafter appear.

85 In order to avoid having the gaseous medium undergo too great a loss of temperature when the liquid is supplied thereto to be vaporized, I cause the water flowing to the tank 46 to receive a preliminary heating. 90 The object is to raise its temperature and is attained by passing the water through the water jacket of the expansion cylinders in the manner outlined in the next paragraph.

46 represent outlets for the tanks 46, and 95 47 represent pipes connecting the tanks 46 to the water jackets 48 of the cylinders 1 and 3.

48' represent supply pipes which conduct cold water to these water jackets, and these pipes may communicate with a pump for 100 keeping the supply continuous. The water passes into the jackets cold and is more or less heated when it reaches the tanks 46. Consequently, it is heated when it passes into the atomizer pumping attachment to be 105 sprayed into the gases of combustion. The water after leaving the tanks 46 may be cooled for further use. The pump which supplies water to the pipes 48' may be so constructed as to embody means for regulating the stroke thereof, so as to control the amount of water at will, and it may be operated by the connection with the generator itself or from some other source of power.

110 With the addition of liquid, such as water, to the gases, the generation of a suitable pressure medium by my system is practically completed. However, in addition to the parts above set forth, I employ a suitable combination of passages for conducting the 120 pressure gases to a reservoir, into which the gases are allowed to flow, and from which they are immediately withdrawn to be used to run engines or for other power purposes. These passages are arranged as below set 125 forth.

The numeral 49 represents a flanged ring on the top of the air compressor cylinder 3, and it contains a valve 49' which controls a port leading through the wall of the air 130

compressor cylinder 3 to the space between the pistons 21. On the top of this ring is bolted a casting 50. This casting has a bore 51 through the same, into the ends of which 5 the pipes 33 are screwed; and 52 are openings or recesses leading by way of ports 53 through the surface of a valve seat 54 in the top of the casting, this valve seat receiving a valve 55. There is free communication 10 around the walls of the bore 51 from the space above the valve 49' through the recesses 52 and ports 53, and out through the valve seat 54 when the valve 55 is raised, so as to permit any gases between the pistons 15 21 to pass around the walls of the bore 51 past the valve 55 when the same is open. The valve is provided with a valve cage 56 bolted to the top of the casting 51, this valve cage being in the form of a short section of 20 piping, and in the end of this section is screwed a delivery pipe 57, which leads to the reservoir or equalizer chamber.

Before taking up the detailed description of the operation of my generator from one 25 end of the process of pressure generation to the other, it is to be observed that the pistons 3 and 4 are intended to do no work except to supply air and hydrocarbon to the inside of the cylinder heads 14. The pistons 4 actuate 30 the pump pistons 21, and the valves and igniters are so controlled as to admit and fire the combustible mixture at the proper points in the cycle. The operation of the pressure generator is thus automatic and continuous. 35 Most of the gases flow out through pipe 31, receiving liquid from tank 46 and converting the same into steam; and this takes place at both ends of the apparatus as will be understood. A small part of the gases passes 40 by way of ports 7 and 6 into the space between the pistons 21 and into the conduits 57 through valve 49'. As stated above the conduit 57 leads to a reservoir, but the pressure medium is not stored therein; it is simply led into the same, and immediately withdrawn therefrom to be used in the production of power, either by means of an engine or other prime mover or in some other way.

The manner of operation of my invention 50 is as follows: Suppose the two pistons 4 to be in the position shown in Fig. 1, that is, at the right-hand limit of their movement. As soon as the piston 4 at the right has moved the bar 26' connected to the rods 26 joined to 55 the piston 21 which surrounds the right-hand cylinder 4, the valve 9 will be unseated, and as the right-hand pump piston 21 has compressed the air between the same and the flange 2, forcing this air through the 60 pipe 18, in the course of the movements of the pistons 4 and 21 to the right, a combustible mixture under pressure has been stored in the head 14 of the right-hand cylinder. Almost immediately after the cross-bar 26' in question has forced the operating valve

stem 10 to open the valve, the projection carried thereby will close the contacts 24 and 25 to close the ignition circuit, and this will result in a spark at the igniter 23, to fire the charge. It will be understood that I may 70 use an ordinary vibrating coil to energize the igniter 23, for this purpose. The result is that the explosive mixture under pressure in the head 14 ignites and flows out past the valve 9 and moves the piston 4 to the left. 75 As soon as the flange or collar providing the shoulder 22' on the piston at the right uncovers the port 27, a part of the burnt mixture will pass up through the pipe 29, it being understood that at this time the inner 80 end of the sleeve 22 and the shoulder 22' are in contact with each other to close the aperture 7, the piston 4 having moved to a sufficient extent to close the space between this shoulder 22' and the inner end of the sleeve 85 22. The burning gases thus flow out through the pipe 29 past the check valve 29' and into the space between the inner surface of the head 34 and the conduit 36, forcing back the piston 41. This piston thus has a pumping 90 action upon the water between the same and the closed end of the head 34, and the result is that some of this water is forced through the ports 42 into the conduit 36 and up as far as the head of the valve 35. At 95 the same time the pressure of the gases is exerted behind the valve 35 through the apertures 38 in the head 37, moving this valve to open position against the action of the spring on the outer end of the same. 100 The gases and water thus mix, and this mixture passes into the casing 50. As the pistons continue their movement to the left, the port 28 will be opened and the bulk of the burning gases will pass out through the pipe 105 31 into the coupling 32, mixing with the gases containing the water, and the entire volume of the charge mixed with the steam formed in this way will force the valve 55 from its seat and pass out into the delivery 110 pipe 57.

It will be understood that the water injected into the coupling 32 will be vaporized by the bulk of the gases passing through the pipe 31, and that the gases passing through 115 the pipe 29 serve mostly to force the water into the body of said gases. At best only a small part of the water is vaporized by the gases in the pipe 29.

As the piston 4 at the left moves into the 120 left hand cylinder 1, the left-hand pumping piston 21 will be forced toward its pipe 18 and carbureter 16, to force fuel into the head 14 of the left-hand cylinder. As soon as the rods 26 carrying the bar 26' close 125 the circuit of the ignition devices at the left, the gases in the head of the left-hand cylinder will be ignited and the same operation will be repeated. It will be noted that the bar 26' of the right-hand cylinder will 130

cause the valve of the right-hand cylinder to close as soon as the pistons have moved far enough to make the bar 26' engage the collar 10'.

5 As stated above, the sleeves 22 are slightly shorter than the distance between the flanges 5 and the flanges or shoulders 22'. Consequently, when the piston 4 in the right-hand cylinder returns into its cylinder the 10 flange 5 will not move the piston 21 until the piston 4 has moved to such an extent that the sleeve 22 will uncover the port 7. The flange 22' is of less width than the diameter of the port 28, and when the flange or collar 15 passes this port 28, any residual burnt gases in the right-hand cylinder 1 will pass around the flange 22' and through the apertures 7 to the inside of the right-hand piston. These gases will pass out through the opening 6 in the flange 5 to the space between the 20 pistons 21, and when the pressure of the gas in between these two pistons 21 is high enough, the valve 49' will be lifted, and these gases will pass up after the other 25 gases into the pipe 57, flowing through the apertures 52 and the ports 53, and through the valve seat 54 in this way. As the right-hand cylinder piston continues its inward movement, the sleeve 22 will pass the ports 30 27 and 28 until there is no further flow from the interior of the cylinder 1 through the port 28. Each sleeve 22 of course covers the port 7 in its respective piston when the piston moves outward.

35 The cylinders 1 between the valves 9 and the heads 4' carried by the pistons 4, form expanding chambers into which the burning fuel expands after being ignited. The head 34 with the valve 35 therein constitutes an injector or aspirator through which 40 warm water is supplied to the burning gases which pass into the connection 33. The water is forced out past the valve 35 by the piston 41 actuated by the gases flowing 45 through the pipe or conduit 29, and these gases also flow through the apertures 38 to lift the valve 35 from its seat; and the water which flows out past the valve when 50 the valve moves from its seat is vaporized by the body of the gases passing through the pipe 31 and converted into steam.

It will be understood that check valves will be employed in connection with the carburetor 16 to prevent the explosive mixture when ignited from firing back into the carburetors, and these check valves may be conveniently located in the pipes 15. It will be noted that the plunger 11 fits snugly in the dash-pot 12, and when one of the pistons 60 through its engagement by the flange 5 with the pumping piston 21 causes the cross bar 26' to open one of the valves 9, the pressure of the burning gases inside the head 14 will be great enough to hold the 65 valve open, even when the piston starts on

its outward stroke; that is, this pressure will hold the plunger in the dash pot 12 until the greater part of the gases has been discharged from the inside of the head 14 through the partition 8 into the cylinder 1, 70 and out through the ports 27 and 28 to the delivery pipe 57. On the return stroke of each piston the greater part of the exhaust gases remaining in the cylinder 1 is discharged through the apertures 7, the interior of the piston and the apertures 6, taking this path around the flange or collar 22' as it passes the port 28, which will of course have the required dimensions to make this mode of operation possible. The burnt 75 products of combustion remaining in the cylinders 1 can thus be cleared out of the cylinders.

It will be noted that the valves 9 are opened by the bars 26' engaging the heads 80 10' when the pistons are at the inner ends of their strokes. When the pistons are at the ends of their out-strokes the valves are closed by the bars 26' engaging the collars 10'. As each of the pistons starts on its stroke the 90 valve 9 thereof will be held to its seat by the gases entrapped between the dash-pot 12 and plunger 11, and the pressure of the gases between the partition 8 and the head 4' will not rise to a sufficient extent to lift the valve 95 9, owing to the fact that these gases will flow around the flange 22' and into the casing 3' between the pistons 21, as above described. When the flange 22' passes the port 27, whatever gas remains in the cylinder 1 is of 100 course compressed, but by the time the compression reaches a sufficient value to force the valve 9 off its seat, the bar 26' will be almost in position to engage the head 10' and open the valve any way. In other 105 words, the combustible charge will have been forced into the interior of the head 14' and be ready for ignition, so that, even if the valve 9 should open a little before the head 10' is engaged by the bar 26', the operation 110 of the apparatus would not be interrupted. Ignition would take place as soon as the circuit is closed by the projection on the bar 26' forcing the contacts 24 and 25 together. I may attach a counter to be operated by the 115 rods 26 to record the number of strokes of the generator, and I may use compressed air as a starting agent. The compressed air may be stored in separate tanks, each of which will be connected to the casing 3 120 through one of the flanges 2 by a suitable conduit having a valve therein. When the tanks are filled the valves can be closed and the air thus stored in the tanks allowed to flow into the casing 3 against one or the 125 other of the pistons 21, to communicate motion to one of the pistons 4 for the first one or two strokes, after which the compressed air can be cut off and the apparatus allowed to operate in the usual way. The position 130

of the rods 26 will indicate the end to which the compressed air is to be directed at first to set the pistons 4 in motion. In practice I intend to use my power generators in batteries of from three to ten, having them all discharge into a common equalizer chamber or reservoir. The pressure medium will be drawn from this reservoir and used in engines of various kinds, and the motive agent which the gases produced by my generator constitute, will do away with the necessity of furnaces, stokers, boilers and other apparatus which have heretofore been necessary to use in steam power plants, ships, etc.

I claim as one of the most important advantages attending the use of my invention, that by means of my generator I can save and make available for power purposes all the heat energy of the gases generated. The hot flames and gases resulting from the explosion taking up the water from the aspirator create steam, and the water which is used in the production of steam is given its preliminary heat by passing it through the water jacket of the power cylinders 1. The amount of heat thus necessary to converting the water passing through the aspirator into steam vapor is reduced, and the mixture of steam and gases of combustion retain the largest possible amount of heat in their passage through the delivery pipe 57 to the equalizer chamber, and thence to a point where they are to be applied.

The capacity of the entire apparatus can be regulated by means of the valves 19, 30 and 45. The valve 19 will regulate the amount of air passing through the carbureter 16 and thus the amount of fuel, and the valves 30 and 45 will regulate the amount of water that is converted into steam to be mixed with the gases passing out through the pipes 31.

The valves 20' which admit air to the air compression chambers are the most important part of the control of my generator. These valves regulate the quality of the combustible mixture and thus determine how much water can be vaporized by my apparatus.

It will now be clear wherein the advantage and utility of my invention resides. The mechanism shown and described can of course be greatly varied and simplified; and in fact I desire to reserve to myself the right to use any apparatus which will enable me to generate pressure in the manner above disclosed. I employ the internal combustion principle, but I utilize it in such a way that the thermal losses that are incurred with apparatus of this general type are entirely obviated. In an ordinary gas engine the major portion of the heat developed by combustion is thrown away in the exhaust or absorbed by the cooling liquid. I utilize and apply the heat of the exhaust from the cyl-

inders 2 to create steam, and I utilize the water jackets of the apparatus to warm the water used to form steam. Thus what are usually considered as serious drawbacks in the employment of the usual kinds of internal combustion apparatus are converted into positive advantages in my invention; and a highly effective pressure medium is obtained at a very low cost, and with the lowest possible waste and loss of heat liberated in the process.

I wish to have it understood that the above description and the drawings accompanying the same illustrate but one embodiment of my invention, and I do not care to be limited to the details thereof, but wish to reserve to myself the right to make such changes in the shape, size and arrangement of the parts as fairly fall within the scope of my invention, according to the manner in which the same is defined in the accompanying claims.

Having thus described my invention, I claim as new and desire to secure by Letters Patent:

1. A generator comprising a cylinder having a piston therein, a compression chamber at one end of said cylinder, means for closing communication between the said compression chamber and said cylinder, means operated by the piston to open the chamber to the cylinder at the inner end of the piston stroke, and an igniter in said chamber.

2. A generator comprising a cylinder, a piston therein, a compression chamber in one end of said cylinder, means for forcing combustible mixture into said compression chamber means closing communication between the chamber and the cylinder, and means operated by the piston at the inner end of the stroke to allow the mixture when ignited to pass into the cylinder to force the piston outward, and an igniter in said chamber.

3. In a generator, the combination of a cylinder having a piston therein, a compression chamber at one end of said cylinder, means for forcing combustible mixture into said chamber, a valve for closing communication between the chamber and the cylinder, means operated by the piston to engage the valve and lift the same off its seat at the inner end of the piston stroke, and means operated by the piston to ignite said mixture, whereby, when the mixture is ignited and the valve opened, the burning gases will pass into the cylinder behind the piston to force the same outward.

4. In a generator, the combination of a cylinder, a piston therein, and a chamber at one end of said cylinder communicating therewith, means for forcing a combustible mixture into said chamber under pressure, said means being connected to said piston

and operated thereby, and an igniter in said chamber.

5. In a generator, the combination of a cylinder having a piston therein, said cylinder having an open inner end, a pump casing adjacent the open inner end of the cylinder, a piston in said pump casing, a pressure chamber in the opposite end of the cylinder, and a conduit affording communication between said pump casing and said pressure chamber, said pump piston being connected to the cylinder piston and operated thereby to force the combustible mixture into the pressure chamber.

15. 6. A generator comprising a cylinder having a piston therein, said cylinder having one end open, a pump casing attached to the said end of the cylinder, a pump piston in said pump casing, said pump piston being concentric with said cylinder piston and operated thereby, a pressure chamber at the opposite end of the cylinder, an air duct communicating with the pump cylinder to discharge air into the compression chamber, 20 and a carburetor through which said air passes to form a combustible mixture on its way to said pressure chamber.

7. In a generator, the combination of a working cylinder, a piston therein, a port in said cylinder, a water injector or aspirator, a pipe connecting said port to said aspirator, and means for supplying combustible mixture to said cylinder and burning the same behind said piston to force the same outward, said piston on its outward movement uncovering said port and allowing the burning gases to pass through the pipe to the aspirator to aid the flow of water through said injector.

40. 8. In a generator, the combination of a working chamber, a piston movable therein, a port through the wall of said cylinder, a water injector or aspirator comprising a pipe having a valve-closed end, a conduit connecting said port with said aspirator, said pipe having a series of openings in the seat of said valve, communicating with said conduit, whereby, when a combustible mixture is burnt behind the piston, the same will be forced outward, and part of said gases will pass up through the conduit and through the openings in the injector past the valve and its seat, a second port located beyond the first-named port in the direction of travel of the piston, a pipe connected to said second-named port, the outer end of said pipe communicating with the discharge end of said aspirator, and a valve-controlled delivery pipe communicating with said last-named pipe and said aspirator, whereby, on the further outward movement of the piston, the greater part of the burning gases in the cylinder will pass out through the second-named pipe past the dis-

charge end of the injector to vaporize the 65 water supplied therethrough, the mixture of hot gases and steam passing out through the delivery pipe.

9. In a power generator, the combination of a cylinder, a piston moving therein, said piston having a circumferential flange at its inner end, a port through the wall of the cylinder adjacent the end of the outward stroke of the piston, a delivery pipe and means for connecting said delivery pipe with 70 said port, whereby the burning gases will escape through the said port when the piston uncovers the same near the outer end of its stroke, said piston having a passage therethrough, one end of said passage being located adjacent the flange on the inner end of the piston, and the other end of said passage being located adjacent the outer end of the piston, and means for connecting said passage with the delivery pipe, the said flange 75 on the inner end of the piston being of less width than the diameter of the port, whereby, when the piston moves inward, the residual gases in the cylinder will pass by the flange through the passage in the piston to 80 the delivery pipe by a different path from that taken by the body of the charge in passing through said port.

10. In a generator, the combination of a pair of opposed cylinders, the adjacent ends 95 of said cylinders having laterally-extending flanges, a cylinder connecting said flanges forming a compression chamber, a piston in each of the opposed cylinders, a piston surrounding each of said pistons, said second-named pistons being located in the compression chamber, said compression pistons being movable with respect to the pistons in the power cylinders, a pair of rods connected to each of said compression pistons and passing 100 out through said flanges along the sides of the power cylinders, cross-bars connected to the outer ends of each of said pair of rods, and means operated by said cross bars to control the operation of said power pistons 110 and said compression pistons.

11. In a generator, the combination of means for forming heated gases, means operated by the pressure of the gases for supplying liquid to said gases to be vaporized 115 by the heat of the same, and means for bringing said liquid into contact with said means for forming heated gases to subject the same to a preliminary heating before the said liquid is brought into contact with the 120 said heated gases.

12. In a generator, the combination of a combustion chamber, a water jacket therefor, means for conducting said gases of combustion away from said generator, means operated by the pressure of the gases for supplying water to said gases to be vaporized 125 by the heat of said gases, and means for con-

ducting said water through the water jacket to heat the same before the same is vaporized by the gases.

13. In a generator, the combination of a combustion chamber, an air chamber at one end of the combustion chamber and having a valved controlled outlet, a steam and gas chamber above the air chamber and provided with a valve seat and ports leading through the valve seat, a valve on said seat, and a chamber between the air and steam and gas chambers and with which the said ports in the valve seat communicate.

14. The combination of a cylinder inclosing a working chamber, a piston moving therein and having an annular collar adjacent its inner end, the remainder of said piston being of less diameter than the cylinder, said cylinder having an exhaust port to permit the escape of exhaust gases when the piston is at the end of its out stroke, said port being of greater diameter than the width of the collar to permit the exhaust to continue after the piston starts on its return stroke.

15. The combination of a cylinder inclosing a working chamber, a piston having a collar at one end, the rest of said piston being of less diameter than the cylinder and being hollow, said cylinder having an exhaust port in position to be overrun by the piston at the end of its out stroke, and said piston having apertures leading into the

same on one side of the collar, said collar being of less width than the diameter of the 35 exhaust port, whereby the exhaust can continue after the piston starts on its return stroke, and part of the same pass through the apertures in the piston and escape by another path than through the said exhaust 40 port.

16. The combination of an explosion chamber having an opening and a valve controlling the same, a dashpot and a plunger associated with said valve, means for moving 45 said valve to uncover the opening, and means for burning the combustible gases in said chamber, the pressure of said gases holding the valve in open position.

17. In a generator, the combination of a 50 power chamber having a piston therein, a compression chamber adjacent said power chamber, a piston moving in said compression chamber, said compression chamber having an outlet, and a passageway leading 55 through the first piston to permit part of the exhaust gases from the power chamber to pass through the outlet in the compression chamber.

In testimony whereof I have signed my 60 name to this specification in the presence of two subscribing witnesses.

ELBERT BALL PORTER.
